C. H. YOUNG

RECEPTACLE

Filed Sept. 30, 1926

Fig. 1.

Fig. 2.

Fig. 3.

Inventor:
Clarence H. Young,
by Emery, Booth, Jamney & Varney, Atty's.

UNITED STATES PATENT OFFICE.

CLARENCE H. YOUNG, OF BOSTON, MASSACHUSETTS.

RECEPTACLE.

Application filed September 30, 1926. Serial No. 138,665.

My invention relates to receptacles such as boxes or baskets, and will be best understood from the following description when read in the light of the accompanying drawing of an example of the invention, while the scope of the invention will be more particularly pointed out in the appended claims.

In the drawing:—

Fig. 1 is a perspective view of a receptacle 10 constructed according to the invention;

Fig. 2 is a section in a vertical plane containing the line 2—2 of Fig. 1; and

Fig. 3 is a perspective of three receptacles according to Fig. 1 in stacked or nested 15 relation.

Referring to the drawing I have shown a receptacle which preferably comprises the sheet metal sides 1 and ends 3, the ends being bent to form flanges 5 overlapping the sides 20 1 and riveted thereto by rivets 7. At their lower edges the sides and bottoms of the receptacle are bent to form flanges 9 upon which rests the bottom 11 of the receptacle secured to the flanges by rivets 13.

As illustrated, I have shown a Z-iron 5 bent to extend around the upper edges of the end and side walls of the receptacle, these walls conveniently being bent to form flanges 17 which are secured to the horizontal web 30 19 of the Z-iron by rivets 21, while the lower vertical flanges 23 are secured to the side and end walls by rivets 25.

At the bottom of the side walls 3 I have illustrated flat metal bars 27 which project 35 beyond the sides of the receptacle and are secured to the bottom of the receptacle by the counter-sunk rivets 13, the bars conveniently having the upturned portions 29 riveted to the end walls at 31.

The bars 27, which among other things act to protect the adjacent parts of the receptacle, form a convenient runner for adapting the receptacle to be slid along a floor or other support, or contact with the 45 rollers of a gravity conveyer, and are also adapted to rest upon the horizontal webs of the Z-iron at the top of a similar receptacle. The parts are so proportioned that the distance between the outer edges of the

50 bars 27 is approximately that between the inner sides of upper vertical flanges 33 of the portions of the Z-iron at opposite sides of the receptacle so that when similar recep-

tacles are nested or stacked as illustrated by Fig. 3 the co-acting bars 27 and Z-irons will hold the receptacles in aligned relation.

Although I have described for purposes of illustration one example of my invention it will be understood that within the scope of my invention wide deviations may be made therefrom without departing from the spirit of my invention.

Claims—

1. A metal receptacle having a flat base and vertical sides, said receptacle at opposite bottom edges thereof having runners each formed of a flat bar extending along and beneath the bottom of the receptacle with portions projecting laterally beyond said edges, said receptacle at the edges thereof of above said bars having a reinforcing rim comprising a Z-bar, the web of which Z-bar is placed horizontally and projects laterally beyond the side walls of said receptacle over the laterally projecting portions of said runners, one flange of said Z-bar extending upwardly to form a marginal wall about the outer edge of said web beyond vertical planes including the outer edges of said runners, the other flange of said Z-bar extending downwardly in overlapping relation to the vertical walls of said receptacle, to which flange said walls are secured.

2. A metal receptacle having a flat base and vertical sides, said receptacle at opposite bottom edges thereof having runners each formed of a flat bar extending along and beneath the bottom of the receptacle with portions projecting laterally beyond said edges, said bars at the ends thereof being bent upwardly to form corner protecting portions for the bottom of said receptacle, said receptacle at the upper edges thereof being formed with a laterally projecting reinforcing rim comprising a laterally projecting flange and an upwardly projecting wall at the outer margin of said flange, the runners of a like receptacle being adapted to rest upon said laterally projecting flange of said reinforcing rim between opposite portions of said upwardly projecting wall.

In testimony whereof, I have signed my name to this specification.

CLARENCE H. YOUNG.
